UNITED STATES PATENT OFFICE

CLARENCE D. TRUSSELL, OF POUGHKEEPSIE, NEW YORK, ASSIGNOR TO TRUSSELL MANUFACTURING COMPANY, OF POUGHKEEPSIE, NEW YORK, A CORPORATION OF NEW YORK

COVER FOR LOOSE-LEAF BINDERS AND METHOD OF MAKING THE SAME

Application filed June 21, 1928. Serial No. 287,334.

This invention relates to the manufacture of covers for ring books or similar temporary binders, the covers being of the built-up or composite type. This type of cover is constructed generally after the method long used in making book covers by binders; that is to say, there is an outer covering fabric which extends over the back and sides of the cover, the sides being stiffened by boards cemented to the covering fabric, the latter being turned in around the edges of the boards and a lining fabric applied to the inner face of the sides of the cover to form a neat finish. When such covers are used for loose-leaf books it is common to employ a curved metal plate which is fastened to, or built into, the back of the cover, so as to stiffen it, and which also forms the foundation for the split ring loose-leaf binding mechanism.

The present invention aims to facilitate the manufacture of such book covers by simplifying the process so as to save labor; and it also aims to produce a more perfect and stronger cover of greater durability.

In the making of such composite covers for ring books, it has heretofore been customary to apply one or more binding strips of suitably tough fabric as a means for anchoring the metal back plate of the book to the back of the cover, usually by confining the plate between such strip and the outer covering, and gluing the edges or flaps of the strip to the cover sides. An example of such construction is found in my Patent No. 959,182, dated May 24, 1910.

According to the present invention a fabric binding strip is employed, but it is glued directly to the outer covering along the back of the book, and its flaps are not glued to the sides of the book, but are free and are turned over upon the inner or upper side of the metal back plate after the cover has been substantially completed and the back plate is fitted thereto. Heretofore the curved metal back-plate has been glued to the back at the time of forming the cover, which precluded rolling down the layers or piling the covers flat in compact stacks. The present invention enables the covers to be substan-

tially completed and rolled flat and stored in flat stacks, before the rounded back plates are attached. The process of manufacture and the advantages of this construction of cover will be hereinafter set forth.

In the accompanying drawings,—

Fig. 1 is a perspective view showing the cover partially completed, and before the insertion of the back plate, the lining being partly turned back.

Fig. 2 is a transverse section approximately in the plane of the line 2—2 in Fig. 1.

Fig. 3 is a longitudinal section through the book back, cut approximately on the line 3—3 in Fig. 1.

Fig. 4 is a section in the same plane as Fig. 2, but showing the cover after the introduction of the metal back plate.

Fig. 5 is a plan of one end portion of the binding strip.

Referring to the drawings, *a* designates the covering fabric which covers the entire exterior of the book cover and is also folded over the edges of the side boards and the ends of the back in the manner usually practised in making book covers; *b b* are the side boards for stiffening the sides of the cover; *c c* are the cover linings; and *d* is the binding strip.

To construct the cover, the covering fabric *a* is cut to a size sufficiently larger than the dimensions of the completed cover when laid open flat, to afford suitable margins for turning in around the edges of the side boards. This covering fabric, which may be of leather or woven fabric, or any suitable material, then has a coating of adhesive (glue) applied to its inner surface, preferably by running it through a gluing machine. Being then laid down flat with its glued face uppermost, the binding strip *d* is applied to the glue-coated surface of the middle or back portion of the covering fabric. This strip is first cut to proper size and its corners *e e* are cut out,

as shown in Fig. 5, and its lateral flaps *d'* are folded inward, but leaving the tongue or end flap *f* between the cut-out portions *e e* unfolded. The middle portion of the binding strip is thus glued fast to the covering fabric, while its flaps are left free. The stiffening boards *b b* are then laid onto the glue-coated

surface *a* (Figs. 2, 3, 4) of the covering fabric in such positions as to correctly locate the sides of the cover and leave sufficient space between them for the book back and for the flexible zones *g* which constitute the hinge portions. The projecting marginal edges of the covering fabric are then turned in upon the outer edges of the stiffening boards, and in so doing the ends *f* of the binding strip, which have been cemented to the covering fabric, are turned in. In this condition the unfinished cover is subjected to pressure to unite the cemented surfaces and is put away to dry or partially dry. The pressure is best applied by running it between rollers, preferably elastic rollers, such as a wringer; and to hold the covers flat during drying they are best placed between sheets of binders' board and held under pressure by means of a weight or by being placed in a press.

The linings *c c*, having been cut to proper size, have adhesive applied to their back surfaces, preferably by running them through a gluing machine. The linings are then applied to the sides of the cover, so that they cover over the turned-in portions of the outer covering and conceal the stiffening boards. Their inner edges also overlie and are cemented to the flaps *d'* of the binding strip. The unfinished cover in this condition is then again subjected to pressure and dried, or partially dried, preferably by running through a wringer and placing between boards as before.

When the cover thus made has been properly seasoned, it is ready for the insertion of the metal back plate, lettered *h*. Preparatory to this, the flaps *g* of the binding strip are opened out and the end flap *f* at one end is turned outward after first cutting slits *i i* through the inturned covering fabric, so that the intervening portion of covering fabric, forming a flap *j* (Fig. 1), and which is cemented to the end flap *f*, is turned outward. This is done at one end only, so as to leave the other end as a closed pocket. The back plate *h* is then introduced at an angle, as shown in dotted lines at *h'* in Fig. 3, so that one end is inserted into the end pocket in the binding strip at one end, and by holding bent outward the flaps *j, f*, at the other end, the back plate is carried down and inserted within these flaps, which are then turned inward to confine it as shown in Fig. 3. To facilitate this operation the back plate is made somewhat shorter than the book back. The operator then, by means of a brush, will coat the inner sides of the flaps *d'* and also the end flaps *f*, with glue, and will turn them down so as to glue them fast to the inserted metal plate. In this operation the book back is curved to conform to the shape of the metal plate, as shown in Fig. 4. It is then necessary to subject the cover to pressure to hold it in shape until sufficiently dry; and for this

purpose the cover may be laid upon a supporting surface which is concaved along the book back so as to conform to the exterior shape of the back of the book, and a similarly curved piece is laid on the inner or upper side to hold down the flaps while the glue is setting, which may be done by placing a suitable weight on the back portion of the cover.

It is customary to form the back plate *h* with upturned ears or tongues *k*, which, when the back plate is inserted, project up between the inner or approaching edges of the flaps *d'*. It is also customary to apply an inner concaved metal plate *m*, shown in cross-section in Fig. 4, to the inner side of the book back, this plate serving as the base or foundation of the binding mechanism of the ring book or other form of loose-leaf binder. The plate *m* has the usual slots to receive the tongues *k*, and when it has been fitted closely against the inner side of the book back the tongues *k* are turned down and clinched fast to hold the metal plate *m* securely in position. It results from this construction that the flaps *d'* with their attached portions of the inner edges of the lining, are clamped fast between the two metal plates, whereby any disturbance of the position of the flaps is prevented, even if the glue or other cement used should fail to hold.

The proportions are such that outside of the rounded stiffened back portion thus formed, and between this and the inner edges of the stiffening boards *b*, there is left a space or zone *g* on each side which is formed by the outer fabric *a* and the inner lining *c* alone, so that it is quite flexible to serve as a hinge between the back and side.

Heretofore the method of making composite book covers of the character to which the present relates, that has been most generally practiced, was to coat the inner surface of the outer covering material with glue, lay the metal back plate along the middle thereof, lay on the side boards properly spaced, and then turn in the edges of the covering fabric all around, so that these turned-in edges are turned over the ends of the binding plate; then the linings are glued on covering the inner surfaces of the cover sides, and in some instances covering over the concave face of the curved metal plate, while in other cases the linings are in two pieces which may overlap the metal plate or may not quite meet along its middle. This method of construction has the disadvantage that at the outset the metal binding plate is incorporated with the other elements of the cover which themselves are flat, while the binding plate is rounded, so that it is impossible to run the unfinished cover through rolls for squeezing its layers together, and difficulty also is experienced in stacking the covers between boards to dry under pressure. The present invention enables the unfinished covers at two

different stages of the manufacture, and prior to the application of the curved metal plate, to be run through pressure rollers and to be stacked up flat for drying. At the time the metal plate is inserted the composite portions of the cover are thoroughly cemented and sufficiently dry, and the only new adhesive which is applied is that which is put into direct contact with the metal plate. The present invention thus saves considerable time and much labor in the construction of composite covers of the general type referred to, and accomplishes a great saving in storage space for the stacking of the unfinished covers. The present invention makes an extremely durable cover because its back is strengthened by the binding strip and the latter is turned in against the metal back plate and confined between the two metal plates.

In practicing the invention any suitable materials may be used. The outer covering *a* is commonly made of leather or some leather-like material or leather substitute, although for cheaper covers a woven fabric may be substituted. The boards *b b* may be any form of binders' board, either stiff or flexible, according to the type of cover to be made. The linings *c* are usually made of paper. The binding strip *d* is best made of a tough woven fabric having considerable strength. The function of the linings *c* is almost wholly ornamental, and they might be omitted if a neat finish were not desired.

While I have described the preferred mode of practicing the invention, yet it may be modified or varied somewhat within the scope of the appended claims.

I claim as my invention:

1. The method of making a composite book cover which consists in coating the inner surface of an outer covering with adhesive, folding inwardly the longitudinal margins of a binding strip to form side flaps and applying the middle portion of the binding strip to the back portion of the coated covering, applying stiffening boards to the side portions of the covering, then pressing the superposed layers together until sufficiently dry, then opening out the folded flaps of the binding strip and inserting a back plate within such flaps and holding said flaps down on the plate.

2. The method of making a composite book cover which consists in coating the inner surface of an outer covering with adhesive, folding inwardly the longitudinal margins of a binding strip to form side flaps and applying the middle portion of the binding strip to the back portion of the coated covering, applying stiffening boards to the side portions of the covering and turning in the edge portions of the covering over the edges of the side boards, then pressing the superposed layers together until sufficiently dry, then

opening out the folded flaps of the binding strip and inserting a back plate within such flaps and folding said flaps down on the plate.

3. The method of claim 1, with the addition of the applying of linings to the inner portions of the cover sides with an interposed coating of adhesive, said linings lapsing over onto the in-folded side flaps of the binding strip.

4. The method of claim 2, the end margins of the binding strip being secured to the adjacent edge portions of the covering, said end margins and edge portions being folded inwardly together to form a pair of end flaps, the back plate being then inserted beneath both end flaps and secured in place by adhesive.

5. The method of claim 2, the end margins of the binding strip being secured to the adjacent edge portions of the covering, said end margins and edge portions being folded inwardly together to form a pair of end flaps, one of said end flaps being slitted and then lifted, the back plate being then inserted beneath both end flaps and secured in place by adhesive.

6. The method of claim 2, the corners of the binding strip being cut out to provide end tongues, said tongues being secured to the adjacent edge portions of the covering, said tongues and edge portions being folded inwardly together to form a pair of end flaps, one of said end flaps being slitted and then lifted, the back plate being then inserted beneath both end flaps and held in place by adhesive.

7. A book cover comprising an outer covering fabric, stiffening side boards cemented thereto, a binding strip having its longitudinal margins folded inwardly forming side flaps and its middle portion cemented to the middle back portion of the covering fabric, the projecting edges of the latter folded in around the edges of the side boards and overlying the ends of the binding strip, and a back plate overlying the middle portion of the binding strip and inserted under the folded side flaps thereof.

8. A book cover comprising an outer covering fabric, stiffening side boards cemented thereto, a binding strip having its longitudinal margins folded inwardly forming side flaps and its middle portion cemented to the middle back portion of the covering fabric, the projecting edges of the latter folded in around the edges of the side boards and overlying the ends of the binding strip, and a back plate overlying the middle portion of the binding strip and inserted under the folded side flaps thereof and into pockets formed by the infolded ends of said binding strip and covering fabric.

9. A book cover comprising an outer covering fabric, stiffening side boards cemented

thereto; a binding strip having its longitudinal margins folded inwardly forming side flaps and its middle portion cemented to the middle back portion of the covering fabric, the projecting edges of the latter folded in around the edges of the side boards and overlying the ends of the binding strip, a back plate overlying the middle portion of the binding strip, and linings adhesively secured over the stiffening side boards and binding strip side flaps and inserted under the folded side flaps thereof.

10 In witness whereof, I have hereunto signed my name.

15 CLARENCE D. TRUSSELL.
